TONE AMPLIFIER

Filed April 9, 1928

UNITED STATES PATENT OFFICE

GUSTAV A. FUDE, OF SAN FRANCISCO, CALIFORNIA

TONE AMPLIFIER

Application filed April 9, 1928. Serial No. 268,406.

This invention relates to a tone amplifier such as used in conjunction with radio loud speaker units, phonographs and the like.

It is known from actual experience and investigation that the average tone reproducing instrument in use to-day is not capable of amplifying with equal efficiency all the possible frequencies within the range of hearing. The amplification curves of even the best horns, for example, show very great irregularities. Horns usually amplify the upper ranges of frequencies more or less satisfactorily but give only selected amplification to the lower frequencies. Cones amplify the lower frequencies more efficiently but fail usually to handle the upper tones so well.

The object of the present invention is to generally improve and simplify the construction and operation of tone amplifiers, and particularly to provide a tone amplifier which will combine the better qualities of the horn and cone types of tone amplifiers.

The invention, briefly stated, comprises a tone amplifier in which is formed a flat resonance chamber having a constant dimension or spacing between its walls in one direction and a gradually increasing space between its walls in a direction at right angles to the first dimension. The apex or narrow end of the chamber is connected with the speaker unit and the wider end of the resonance chamber is provided with a series of openings through which the sound waves discharge.

The invention is shown by way of illustration in the accompanying drawings in which:

Fig. 1 is a front view of the tone amplifier.

Fig. 2 is a vertical cross section taken on line II-II, Fig. 1.

Referring to the drawings in detail, A indicates a base member of suitable shape on the central upper portion of which is mount-

ed the tone amplifier. The tone amplifier may assume varying shapes but is in this instance shown as circular or disc shaped. It consists of a back plate B around which is formed an annular flange or rim 7. Set 50 forward of the back plate and spaced therefrom to form a resonance chamber 9 is a front plate 8. This plate is provided with a number of slots, such as indicated at 10, and a number of peripheral openings such as indicated at 11, the openings 10 and 11 forming openings through which the sound waves discharge, as will hereinafter be described. The base A and the plates B and 8 may be constructed of a number of different materials, such as plaster of Paris, cement, papier-mâché, vulcanized rubber, etc. A number of tone amplifiers, such as here illustrated, have been cast of plaster of Paris and in that instance, a reinforcing wire 65 mesh is placed within the front and rear plates, as indicated at 12, to reinforce and strengthen the same. The surfaces of the plates may be finished in any suitable manner, for instance with varnish, shellac or the like, and they may be colored or finished to suit varying conditions. If the tone amplifier is constructed of plaster of Paris, an internally threaded sleeve such as indicated at 6 is secured in the lower end of the resonance chamber, this sleeve being provided with projecting arms or wire which is wound about the same so as to thoroughly anchor it and secure it in the cast material. The sleeve serves the function of securing and supporting a loud speaker unit, such as indicated at C. Any suitable type of unit having a diaphragm such as indicated at 4 may be employed. The diaphragm is mounted within a casing, as shown, and it is actuated by a 85 magnet in an armature which is connected with the diaphragm in the usual manner.

The tone amplifier here illustrated might be likened unto a horn which has been flattened as it provides a resonance chamber 90

which is flat, the spacing between the front and rear walls B and 8 being the same while the spacing between the opposite walls of the rim 7 increases from the ferrule or entrance opening 6 due to the circular shape of the plates 8 and B. In other words, a flat resonance chamber is provided which has a constant dimension or spacing in depth and which gradually increases in width from an entrance point to a discharge point.

Before describing the operation of the device, it might be stated that a horn is essentially a resonance chamber which amplifies the sound of the loud speaker diaphragm by virtue of the fact that the air column confined within the resonance chamber is forced into vibration in unison with the vibration of the diaphragm. If a horn should happen to be cylindrical in shape, it would respond only to tones whose wave lengths are twice the length of the tube or to tones whose wave lengths are such that the tube is exactly one-third, one-fourth, one-fifth of them, etc., for example if the tube or cylinder is approximately 27 inches in length, it will respond to medium C, 256 vibrations per second, to C' (=512), to G' (=768), etc. The intermediate tones would in that instance not be amplified.

Since a cylindrical resonance tube responds only to selected tones, in order to reproduce the whole range of audible tones with cylindrical resonators, it would require a series of resonance pipes like a concert pipe organ. Such a tone amplifier would, of course, be out of the question in the average residence. The effect of a multiple series of resonance tube may, however, be secured by gradually increasing the diameter of the tube from its mouth outward toward the bell and the average horn type of speaker or horn amplifier is the result. However, horns will not give true reproduction unless they are built in sizes up to twenty-five or thirty feet in length and this is, accordingly, impractical for average home use.

The cone type of loud speaker depends upon another principle of sound amplification. The loudness of the tone or sound at a given distance from its source may be increased by increasing the amplitude of the vibration, i. e., increasing the actuating forces or by increasing the area of the vibrating object. The cone accomplishes this purpose by presenting a larger surface of coupling with the air and as such does away with the necessity of using a horn. The surface of the cone must in reality vibrate in numerous irregular segments if it is to amplify all the elements of the complex tones. The higher the frequency of the notes sounded, the smaller must be the vibrating segment. Since the factors of texture and elasticity establish a limit to which the segments may be reduced, a vibrating cone cannot amplify

sounds whose frequencies pass a fixed upper limit if it is at the same time to amplify the bass notes for which it is especially suited. The upper partials in sound reproduced by a cone, are accordingly absent where it is desired to bring out the lower tones. The horn, on the other hand, reproduces the higher frequencies and it is accordingly evident that it would be desirable to combine the advantages of the cone with those of the horn.

The tone amplifier forming the subject matter of the present application combines these features as it is provided with a resonance chamber with such a rate of increase in its width that the best advantages of the horn are retained. The front and back walls of the chamber which are equally spaced form sounding boards. These sounding boards preserve the amplification ratio for the lower notes while the rapid rate of increase in width of the resonance chamber in the other direction, amplifies the upper notes, and faithful, harmonious tone amplification is the result.

While certain features of the present invention are more or less specifically described, I wish it understood that various changes may be resorted to within the scope of the appended claims; similarly, that the materials and finishes of the several parts employed may be such as the manufacturer may decide or varying conditions or uses may demand.

Having thus described my invention, what I claim and desire to secure by Letters Patent is:—

1. A tone amplifier comprising a back plate, a front plate spaced therefrom and parallel with the back plate, a flange surrounding the plates and connecting the same, said flange and plates enclosing a resonance chamber, said flange having an inlet opening formed at its base adapted to be connected with a speaker unit, and one of the plates having a plurality of sound outlet openings formed in its peripheral edge and in communication with the resonance chamber.

2. A tone amplifier comprising a front and back plate, said plates being spaced apart and parallel, a flange surrounding the plates and connecting the same, said flange and plates enclosing a resonance chamber, said front plate having a plurality of cut away portions in its peripheral edge and adjacent one end of the flange, said cut away portions forming outlet openings for the resonance chamber, and said flange having an opening formed in its opposite end, to form a connection for a speaker unit.

3. A tone amplifier comprising a front and back plate, said plates being spaced apart and parallel, a flange surrounding the plates and connecting the same, said flange and plates enclosing a resonance chamber, a plurality of cut away portions in the peripheral

edge of the front plate and adjacent one end thereof, said plate also having a plurality of elongated openings formed therein, said cut away portions and elongated openings forming sound outlet openings for the resonance chamber, said flange having an opening formed in its opposite end, a speaker unit connected with said opening, and a base member supporting the plates and adapted to support and surround the speaker unit.
